JAMES BLAKENEY, OF SPRINGFIELD, OHIO.

Letters Patent No. 103,130, dated May 17, 1870.

IMPROVEMENT IN RAILWAY-CAR COUPLING.

The Schedule referred to in these Letters Patent and making part of the same

To all whom it may concern:

Be it known that I, JAMES BLAKENEY, of Springfield, in the county of Clark and State of Ohio, have invented certain Improvements in Automatic Car-Couplings; and I do hereby declare that the following is a full, clear, and exact description thereof, reference being had to the annexed drawings making part of this specification, in which—

Figure 1 is a longitudinal sectional elevation of two buffer-heads for coupling cars together, constructed according to my improved plan, the arrangement of the parts being clearly shown therein.

Figure 2 is a plan or top view of one of the buffers shown in fig. 1, a portion of the spring being broken away, to show the chain which connects the buffer-head to the main-stay or brace which extends under the car from one buffer to the other.

Figure 3 is a front-end view, showing the coupling-pin in position.

Figure 4 is a vertical sectional elevation of a portion of the buffer, showing the devices for holding the coupling-pin in its elevated position.

Corresponding letters refer to corresponding parts in the several figures.

This invention relates to that class of devices which are termed automatic car-couplings; and

It consists in the construction, combination, and arrangement of its parts, as will be more fully explained hereinafter.

The great desirableness of an automatic car-coupling which will with certainty connect cars to each other when placed in the proper positions, and which will not allow them to become detached when in motion, has long been felt and acknowledged; and the object of this invention is to supply this want by providing the means of holding the coupling-pin of one car and the link of another in such positions that, when the two are brought together with any considerable degree of force, the operation of coupling shall be automatically, and yet certainly performed, and, at the same time, the parts necessary to perform the act of coupling be placed in such positions as to render it impossible that the cars should become detached from each other while in motion without the breaking or derangement of the parts; the uncoupling or detaching of the cars at the proper time being accomplished in the most approved and usual manner by withdrawing an ordinary coupling-pin.

To enable those skilled in the art to make and use my invention, I will proceed to describe its construction and operation.

A in the drawings refers to a buffer-head, which may be of cast or wrought metal, and of the form shown in the drawings; or its form may be varied, to adapt it to any form of frame in which it may be placed.

In any event, it is to have the recess or cavity in its front or outer end, for the reception of the coupling-link, the levers and slide which hold the coupling-pin, and a hole through the upper and lower portions thereof, through which to insert such coupling-pin. The rear ends of the bars or plates constituting the rear or inner portion of the head are to be united by a plate, as shown, for the purpose of strengthening them, and for the further purpose of permitting the chain which unites said head to the main brace or stay-rod, which unites the buffers upon the two ends of the car, to be attached thereto.

B refers to a frame of metal, which is to be constructed as shown in fig. 2, or so that the buffer-head A shall move freely within the same. This frame is to be attached to the body or platform of the car, as shown at C C in fig. 1, and is to be provided with slots in its sides, for the reception of bolts or pins, which support the buffer-head therein, and upon which it moves longitudinally. The rear ends of the bars or plates composing this frame are joined together, as shown, and the bolt which holds the chain F passes through it.

D refers to a coupling-pin, which may be of any approved form of construction, and be attached to the buffer-head, or the frame which carries it, by a chain, in the usual manner.

D' refers to a coupling-link, which is to be of the usual kind, but of the required length to come in contact with the swinging frame D⁴, as shown in fig. 1.

D² refers to a slide, which is made to fit and slide in guides attached to the upper surface of the aperture in the buffer-head, as shown in fig. 3, its rear or inner end being attached to the lever D³, by which it is moved. At the point in this slide which comes directly under the hole through which the coupling-pin passes, when the parts are in the positions shown in fig. 1, there is to be formed an aperture, which should be a little larger than the pin itself, so that, when the parts are in the positions shown in fig. 4, the coupling-pin shall rest upon such slide, and be held in the position shown in that figure.

D³ refers to a lever, which is pivoted to the sides of the buffer-head, as shown in fig. 4, its lower end extending down through the bottom of the buffer-head, and carries upon its lower end a spring, D⁵, which, when it is desired to secure the parts in the position shown in fig. 4, or so that they will hold the coupling-pin in the proper position for dropping when the cars are brought together, hooks over a projection on the under side of the head, and holds them in such position. The upper end of this bar projects above the upper surface of the head, so that it may be operated by the hand of the attendant, and the parts be by it placed so as to hold the pin suspended, and also hold

the link in position to enter the cavity in the car which it is desirable to connect to the one upon which the coupling-pin is suspended.

D^4 refers to a frame, which is pivoted to the lever D^3 , as shown in fig. 4. This frame is provided with an arm, which projects forward from it, as clearly shown in fig. 1, its office being to rest upon and hold the coupling-link in its place when it has been inserted, and the lever D^3 has been carried to the position shown in fig. 1, in order that it may with certainty enter the cavity in the head of the other car, and, at the same time, come in contact with the swinging frame in such car, and thus withdraw the slide sufficiently to permit the pin to drop, and thus effect the coupling of the cars without the necessity of the attendant placing himself between such cars at the risk of his life. In the act of coupling or connecting the cars, the link will be released from the control of the lever and swinging frame, and thus it will be free to move about in the cavity in the buffer-heads, so as to leave it free to accommodate itself to the movements of such heads caused by the uneven surface of the road.

E refers to a spring, which is placed between the rear end of the buffer-head and the frame in which it moves, it being attached thereto by having its ends bent, so as to pass into holes formed therein; or it may be attached in any other convenient manner. The form of spring represented in the drawings is the spiral form, but any other spring may be used, if preferred.

F F refer to eye-bolts, which pass through the cross-bar upon the rear ends of the buffer-head and the frame in which it is supported, their office being to hold the ends of a chain which passes through the spring, and, at the same time, by means of the one in the frame B , to connect the heads to each other by means of a long bolt or stay, which extends from end to end of the car, or by any other suitable means.

F refers to a chain, it being the one above alluded to. It will be seen that it extends from one of the eye-bolts to the other, and that it confines the buffer-head to the frame, and through that to the car, in such a manner that, as force is applied to move the car or train, the strain shall come upon these chains, and not upon the bolts upon which the buffer-head slides in its frame.

Having thus described my invention, What I claim, and desire to secure by Letters Patent, is—

The combination and arrangement of the buffer-head A , the lever D^3 , slide D^4 , and swinging frame D^4 , substantially as and for the purpose set forth.

In testimony whereof I have signed my name to this specification in the presence of two subscribing witnesses.

JAMES BLAKENEY.
